WALL BRACKET FOR AN ELECTRIC SHAVER CHARGING UNIT

Bruce F. Ray, Danvers, Mass., assignor to The Gillette Company, Boston, Mass.

Filed Dec. 18, 1969, Ser. No. 20,563

Term of patent 14 years

Int. Cl. D6—01

U.S. Cl. D33—23

Fig. 1.

Fig. 5.

Fig. 6.

Fig. 2.

Fig. 3.

Fig. 4.

FIG. 1 is a perspective view of a wall bracket for an electric shaver charging unit showing my new design;

FIG. 2 is a front elevational view thereof;

FIG. 3 is a side elevational view thereof;

FIG. 4 is a back elevational view thereof;

FIG. 5 is a top plan view thereof; and

FIG. 6 is a bottom plan view thereof.

The undisclosed side is substantially the same in appearance as the side shown.

I claim:

The ornamental design for a wall bracket for an electric shaver charging unit, substantially as shown and described.
